EXPLOSIVE-OPERATED SHEARS

George A. Barker, Rochester, N. Y.

Application March 1, 1944, Serial No. 524,564

5 Claims. (Cl. 42—90)

(Granted under the act of March 3, 1883, as
amended April 30, 1928; 370 O. G. 757)

1

The invention described herein may be manufactured and used by or for the Government for governmental purposes without the payment to me of any royalty thereon.

The invention relates to explosive-operated tools, and more particularly to a wire-cutting tool adapted to be detachably connected to a shoulder arm, so as to be operated by the discharge thereof.

It is an aim of the invention to provide a wire shears tool of a particularly rugged nature liable in a minimum degree to damage or derangement in the unusually fast and rough action involved in an attack against barbed wire guarded positions under an enemy's defensive fire.

It is particularly an aim to offer a tool of great power, effective on very heavy wire and the like, if necessary.

A further purpose is to present a novel and desirable specific structure for attaining the objects stated and others.

Additional objects, advantages and features of invention reside in the construction, arrangement and combination of parts involved in the embodiment of the invention, as will be more clearly apparent from the following description and accompanying drawings, wherein:

Figure 1 is an elevation of a standard form of carbine heretofore used, on which my invention is incorporated (.30 caliber);

Figure 2 is an enlarged fragmentary vertical longitudinal section of the gun muzzle and tool;

Figure 3 is a section on the line 3—3 of Figure 2;

Figure 4 is a cross section on the line 4—4 of Figure 2;

Figure 5 is a cross section on the line 5—5 of Figure 2;

Figure 6 is a cross section on the line 6—6 of Figure 2;

Figure 7 is a cross section on the line 7—7 of Figure 1;

Figure 8 is a perspective view of the rear sleeve;

Figure 9 is a top view of the sleeve-cylinder, the cylinder being in section.

Figure 10 is a perspective view of a modification of the piston slotted at its inner end so as to keep the ports open initially.

There is illustrated a carbine 10 of conventional form upon which my invention is incorporated, although my invention may be applied to other weapons. This arm includes a gunstock 11, of usual form, on which a barrel 12 is mounted, projected forwardly from the hand rest portion 13 of the stock, and secured to the forward end of the stock by a front stock ferrule 14. Any approved loading and firing mechanism may be employed,

2

the details of which are not illustrated, although semi-automatic fire mechanism is effective with the invention and is commonly employed in the weapon illustrated, using .30 caliber blank ammunition.

In the present instance a wire-cutting shears is illustrated, consisting of a base jaw or blade 15 with an integral rectilinear shank 16 extending rearwardly and adapted to lie closely parallel to the barrel 12 as shown. The base of the blade 15 is defined by a horizontal pivot stud 17 upon which a working blade 18 is pivoted. The blade 15 and shank may be planiform and of uniform thickness throughout, with a continuous rectilinear top edge 19 throughout. The blade and shank are arranged with the top edge slightly below the barrel and with the blade in a vertical plane spaced a distance toward the left from the axis of the barrel bore 20. The blade 15 is formed with a flat inner side 21 arranged to receive a corresponding side 22 of the working blade flatly thereagainst, the stud 17 being headed suitably to hold the blades in proper assembly relation. The working blade is formed with a cam heel end 23 extending upwardly beyond the axis of the barrel, the blade being arranged in a diametrical plane of the barrel. The blade 18 has a short shank 24 extending downwardly and having a pivot opening therethrough extending partly below the cutting edge 25 (which is the lower edge of the blade). Through this opening the pin 17 is engaged.

The rear or cam face 26 of the heel 23 is slightly curved and extends upwardly with a forward inclination approximating a radius at an angle of between five and ten degrees to a vertical radius of the pin 17 when the blade is at its lower full stroke limit of movement as dotted in Figure 2. The top of the cam face extends above the axis 40 of the bore 20 a substantial distance throughout the full movement of the blade from open to closed position.

A rearwardly extending lug or wiper 27 is formed on the lower part of the shank 24, and a leaf spring 28 is mounted on the shank 16, a forward end of the spring being disposed over the wiper, so as to press downwardly thereon and hold the blade yieldingly in elevated open position. The spring tends to assume a rectilinear form, its rear end being anchored by a stud 29 on the shank 16, while a middle seat stud 29' is set in the shank 16 so as to hold the spring bowed downward causing its proper reaction against the wiper lug 27.

55 A barrel engaging sleeve 30 and enlarged piston

chamber or cylinder 31 formed concentrically in one piece are provided, secured to the shank 16, the sleeve and gun barrel being constructed to permit engagement and securement of the sleeve on the barrel removably so that the latter communicates coaxially with the cylinder. While various quick-detachable constructions may be employed for coupling the device to the barrel, including bayonet joints or connections in the present instance I have shown the barrel exteriorly threaded and the sleeve 30 interiorly threaded at the rear part and screwed on to the barrel, a flat 32 being formed at the top of the barrel extending longitudinally over part of the threaded portion of the barrel, and in the sleeve thereover a radial slot 33 is formed, a key 34 being provided to fit in the slot for radial sliding movement therein, and of such radial dimension that when resting on the flat, the outer part of the key is flush with the periphery of the sleeve. A split cylinder clasp 35 is fitted slidably and frictionally on the sleeve, holding the key in place. The enlargement of this mounting around the cylinder affords a shoulder 36 which limits forward movement of the clasp. The lower side of the latter is open sufficiently to clear the shank 16 amply as in Figure 5. In the present instance the sleeve and cylinder member is secured to the upper right hand angular edge of the shank 16 by a longitudinal bead of welding at each side, the shank being slightly relieved (as in Figure 4) beside the cylinder to receive the same with the sleeve lying close against the unrelieved angular edge of the shank as in Figure 5 and 6.

In order to secure the rear end of the shank 16 in firm and safe relation to the barrel, I provide a base sleeve 37 (Figs. 1, 7 and 8), which is a double sleeve, having a lower left hand tube 38 rectangular in cross section and fitted snugly and slidably to the shank 16, and an upper cylindrical sleeve 39 slidable on the barrel, the rear end of this being transversely cut across the top to form a clamp arm 40, out-turned clamp ears 41 being formed on the end of the arm 40 and on the unslit part of the sleeve, both ears being apertured and receiving a bolt 42 thereacross with nut at one end, by which the sleeve is clamped in place to secure the shank 16 against lateral displacement. In this instance the rear end of the sleeve 37 is enlarged to receive as a socket the forward extremity of the stock, the eccentricity of which serves to prevent the sleeve from rotating on the barrel when the sleeve is at its rear limit of sliding movement. It will thus be seen that with the sleeve 37 secured at its rearmost position, the sleeve 37 cannot be rotated for disengagement. The key device 34 is an additional safety feature, making a very rigid, rugged mounting. The sleeve 31, the shank 16 and sleeve 35 in effect combine with the barrel to constitute a supporting frame.

Between the threaded opening in the sleeve 30 and cylinder an interior shoulder 44 is formed, against which the end of the barrel 12 abuts when the sleeve is screwed home, and a barrel part 45 is thus provided slightly larger than the bore 20 but flared longitudinally toward the cylinder 31. The interior of the cylinder is bored to a diameter somewhat more than twice that of the bore of the barrel. The forward end of the cylinder is spaced rearwardly of the open tool position of the cam face 26 a short distance, as in Figure 2, and the bore of the cylinder opens straight and flush through the forward end of the cylinder. The length of this bore is sufficient

for proper reciprocation and working therein of a piston 47, which is itself bored as at 48 from the rear end to a diameter approximately twice the diameter of the gun bore 20. The length of the bore 48 in the piston is approximately four and one-half calibers, and with the cylinder constitutes an expandible chamber 49, the piston initially being engaged against the shoulder 44 and having a head 50 formed with a curved end face 51 against which the heel cam face 26 engages as a stop with the working blade in open position as in Figure 2. The faces 26 and 51 may be otherwise shaped as may be indicated to best apply longitudinal pressure of the piston against the heel 23 with a minimum of lateral resultants of force acting crosswise of the piston head.

The piston is formed with two parallel ears 52 extending forwardly close and slidably beside the heel portion of the blade 18, serving to stiffen the latter.

The cylinder has a lateral port 53 formed in each side thereof, consisting of a narrow slot extending circumferentially over an angle of somewhat more than ninety degrees at the interior cylinder wall, in a plane normal to the axis of the cylinder, the narrow dimension of the slot extending longitudinally of the cylinder and its extent in each dimension depending on the rate of escape of gases desired under operation of the devices, and it may be adapted to the amount of explosive used, and the interval in which desired work is to be performed. The slot is spaced a short distance forward from the shoulder 44 so that it will be uncovered after a short movement of the piston. These ports may be varied in proportions, arrangements, and contours to vary the time of high pressure action of the device and at the same time assure prompt venting of gases and return of the tool to initial condition ready for repeated operation. The forward and rear faces 54-55 of the ports in this instance are sloped rearwardly toward the outside so that upon discharge of products of combustion through the chamber the gun and tool will be thrust forwardly by the reaction of the gases through the ports, and the tool held effectively pressed to the work.

If desired (as in Figure 10), the piston 47 may be shorter than shown in Figure 2, and provided with extensions 56 at top and bottom clear of the ports 53 to hold the piston clear of the ports when the piston is in initial position. The device may otherwise be the same as before described.

The tool shown is provided with one or more notches 57 in one of the blades, to prevent work from slipping forward between the blades while they are closing.

In use, the device being constructed and assembled as in Figures 1 to 8, the loading and firing mechanism of the gun is supplied with blank cartridges with suitable charges of explosive to supply the energy required. This is possible by inserting a conventional magazine or clip 58 in the receiver of the gun in a well known form.

The soldier assigned to wire cutting approaches the fence, entanglement, or other wire obstruction, or material to be cut and thrusts the gun forward so as to receive between the blades 15-18 a strand or a number of strands or bars of the material to be cut, and presses the tool forwardly so that the material is firmly pressed into the angle at the intersection of the opposed edge of the two blades.

The notches 57 will serve to hold such engaged material in place when the blade 18 closes. The

trigger of the gun is then operated to discharge a cartridge in the conventional way. The products of the explosion pass forwardly through the barrel and into the chamber 49 causing initial movement of the piston and operation of the blade 18. The curved face 51 on the piston presses and wipes against the heel cam face 26 effecting the desired movement or stroke of the blade 18 from full open position to fully closed position. In view of this action the device may be classed as a full stroke tool. At the same time, after a short movement of the piston, the ports 53 are uncovered and the backward blast thus produced thrusts the gun and tool forwardly so that tendency of the tool to back off by the rearward force resultants of the closing of the shears upon the work is opposed, and also the forward thrust of the gun will also tend to prevent escape of the work if the latter tends to move forwardly by the effect of the force resultants mentioned.

The operator continues pressing the gun and tool forwardly after the first operation of the trigger and as soon as a sufficient further quantity of material is gathered between the blades, another cartridge is fired, and the operations repeated as required.

By having the ports 53 initially uncovered, forming the piston as in Figure 10, the forward thrust or kick of the gun will occur earlier and will be sustained in proportion to the volumetric value and burning characteristics of the explosive used.

While I have disclosed the invention in its best form thus far perfected by me, it will still be understood that this is exemplary and that changes in form and proportions, construction, arrangement, and combination of parts, substitution of materials and equivalents, mechanical or otherwise, may be made to carry out the intent of the invention without departing from the spirit of the invention.

The enlarged size of the chamber within the piston affords a cushioning means, preventing too abrupt a build-up of pressure in the barrel. This will obviate the need for special slow burning propellant, and also will enable making the tool lighter, as otherwise the parts may have to be made stronger and consequently heavier to avoid deformation by propellants which are too fast burning.

In order to dismount the tool, the rear or base sleeve 37 is released by unscrewing the bolt 42, and the clasp 35 moved slidingly rearward, uncovering the key 34. The sleeve 30 may then be rotated counterclockwise on the barrel, to unscrew it from the barrel, the flat 32 serving as a cam to force the key outward. This feeds the whole tool assembly from the gun. The front sight may then be replaced if it has been removed.

The invention may be readily adapted to other forms of tools, and, in those where sustained pressure against the work is a material factor (which may be termed "pressure effective tools") the inclination of the ports described makes it specially valuable.

I claim:

1. A shears device, in combination with a gun having a barrel provided with a muzzle, comprising a base blade having a rearwardly extended shank, means to attach the shank to said gun muzzle with said blade offset from and extended longitudinally of the barrel, a working blade pivoted on the base blade on an axis close to the end of the base blade transverse to the barrel and spaced from a longitudinal geometrical pro-

jection of the barrel and positioned to swing in a plane aligned with the bore of the barrel, means responsive to gas discharge from the barrel to operate the working blade full stroke in one direction, a longitudinal bar spring mounted on the shank having a forward end adjacent the pivot of the blade, said working blade having a lug thereon arranged to engage the outer side of the spring, said spring being under tension to bear on said lug and hold the working blade yieldingly in open position.

2. In combination with a gun having a barrel provided with a muzzle, a tool constructed for and mounted on the muzzle of said gun, including shear blades arranged to project longitudinally forward from the engaged gun, at least one being movable relatively to the other from an initial forwardly divergent relation toward a closed position, a cylinder fixed in coaxial gas receiving relation to the gun muzzle, a piston slidable in the cylinder and contacting the moveable shear blade, the cylinder being formed with lateral ports near its rear end of small dimension longitudinally of the tool and more extensive circumferentially, the forward and rear sides of the ports being inclined rearwardly whereby vented gases will react against the device to thrust it forwardly against the work.

3. A wire cutting attachment, in combination with a gun having a barrel provided with a muzzle, comprising a frame having a releasable gun barrel connection, a cylinder at the forward part thereof, said cylinder having a lateral vent port open at its forward end and open at its rear end in gas receiving relation to the said gun muzzle, a hollow piston reciprocable in the cylinder, the said piston having a closed forward end and an interior at least two calibers diameter and four calibers length and open to the bore of the said barrel, movable forwardly to clear said port, a stationary shear jaw carried by said frame extended longitudinally at the front of the attachment, a cooperative shear jaw pivoted thereto on a transverse axis offset from the cylinder, said shear jaw having a part extended into the path of the piston and moving longitudinally therefrom in closing movement of the jaw, and resilient means to hold the last named jaw in open position.

4. The combination with a gun having a barrel provided with a muzzle, of a shear attachment comprising a tubular member constructed for and engaged on the muzzle of the said gun, said member being enlarged and bored to form a longitudinal cylinder before and larger than the said gun bore and having a rear gas receiving port arranged to align with the gun bore, a hollow piston slidable in the cylinder having a forward head and an open rear end whereby to form a chamber in said cylinder and piston larger in diameter than the gun bore, a lateral port being formed intermediate of the length of the limits of movement of the rear end of the piston, a shear blade fixed with the cylinder and projected longitudinally forward therefrom, an operating blade cooperative with the fixed blade and pivoted thereon on a pivot axis spaced from the axis of the cylinder, the operating blade aligned with the cylinder, said operating blade having a heel part extending across the path of the piston and resting against the piston head when both are at the rear limits of their movements and open position of the operating blade, the forward longitudinal movement of the heel part being limited to prevent the piston from clearing the cylinder while in opera-

tion, and resilient means to hold the operating blade in open position.

5. In combination with a firearm having a stock and a barrel, a shear member forward of the muzzle and having a shank extending along the barrel, a ferrule having portions fitted on the barrel and shank for sliding motion thereon and having a portion complementary to the forward portion of the stock and means to clamp said latter portion to the stock, a sleeve on said shear member, means to fix said sleeve member on the muzzle end of the barrel, a second shear member arranged for cutting action with the first shear member, and means responsive to gases in the barrel to actuate said shear members.
